UNITED STATES PATENT OFFICE.

WILLIAM H. HARRISON, OF DETROIT, MICHIGAN, ASSIGNOR TO CHICAGO RAILWAY EQUIPMENT COMPANY, OF CHICAGO, ILLINOIS, A CORPORATION OF ILLINOIS.

STRUT FOR BRAKE-BEAMS.

1,070,804.

Specification of Letters Patent. Patented Aug. 19, 1913.

Application filed December 1, 1911. Serial No. 663,452.

To all whom it may concern:

Be it known that I, WILLIAM H. HARRISON, a citizen of the United States, residing at Detroit, Wayne county, State of Michigan, have invented a certain new and useful Improvement in Struts for Brake-Beams, of which the following is a full, clear, and exact description, such as will enable others skilled in the art to which it appertains to 10 make and use the same, reference being had to the accompanying drawings, forming part of this specification, in which—

Figure 1 is a side elevational view of my improved strut for brake beams. Fig. 2 is a 15 sectional view on line 2—2, Fig. 1. Fig. 3 is a sectional view of a modified form.

This invention relates to a new and useful improvement in struts for brake beams, the object being to construct a strut for 20 trussed beams in which the seats for the compression and tension members may be made of malleable casting, while the shank portion of the strut may be formed of commercially rolled bars riveted to said end portions and provided with pin holes for the 25 brake lever pins. By thus constructing a built-up strut, it is possible where any of the parts thereof are damaged in service, such parts may be replaced, and a saving of 30 the remainder of the parts be thus effected.

In the drawings: 1 indicates the compression member and 2 the tension member of a well-known form of brake beam.

3 is a casting provided with a wall 3^a for 35 embracing the compression member, said compression member being clamped in position by a wedge key 5 as shown in Fig. 1.

3^b indicates an inward extension formed on this end casting to which the shank bars 40 6 are secured, preferably by means of rivets 7.

8 is the casting at the opposite end of the strut which provides a seat for the tension member 2 and which may also have a perforated lug 10 for the attachment of the third suspension link, if desired. This casting 8 also has an inward extension 8^a to which the 45 ends of the shank bars 6 are connected by means of rivets 11. The pin holes 6^a in the 50 shank bars are preferably formed by punch-

ing the metal of commercially rolled bars, so as to form bosses 6^b around said openings in a manner that is well known. The pin holes 6^a are formed in the bars 6 "off center" or closer to one end of said bars than 55 the other, and thus by reversing the positions of the bars or turning the same end for end the location of the pin holes is changed with respect to the tension and compression members, which arrangement is very desirable 60 where it is necessary to change the position of the brake lever.

If desired, the bars may be flat, as shown in Fig. 2 or convex as shown in Fig. 3 in which latter figure bosses 6^c are also formed 65 on the inner faces of the bars.

From the above it will be seen that my improved strut is very simple, the several parts being capable of being replaced in making 70 repairs.

By turning the shank bars end for end, the location of the pin hole may be varied according to requirements, thus reducing the 75 number of parts to be carried in repair shops.

Instead of using rivets to fasten the shank bars in position, bolts may be employed, or other fastening devices used, which will enable the ready dismantling of the strut.

What I claim is:

A strut for brake beams comprising a pair of castings adapted to engage the tension and compression members of the brake beam, the casting which engages the compression member being provided with a substantially U-shaped seat for said compression member, and with apertures at one end of said seat, which apertures are adapted to receive a key for locking said casting to the compression member, lugs integral with and 85 projecting inwardly from said castings, a perforated lug integral with the casting which engages the tension member, which perforated lug is adapted to receive the third suspension link of the brake beam, a pair of separate and independent duplicate bars positioned between the castings with the ends of said bars engaging oppositely disposed faces on the lugs, attaching means 90 passing through the ends of the bars and the 95 100

lugs, each of said bars being provided with a single brake lever pin hole, and the pair of holes being located nearer one end of the bars than the other, whereby the location of the brake lever pin holes is changed when the bars are turned end for end.

In testimony whereof I hereunto affix my

signature in the presence of two witnesses, this 25th day of November, 1911.

W. H. HARRISON.
